TEXTILE DRAFTING APPARATUS

William Aldred Hunter, Reginald Mayman Blackburn, and Walter Nutter, Helmshore, Rossendale, England, assignors to T. M. M. (Research) Limited, Rossendale, England

Application February 19, 1952, Serial No. 272,444

Claims priority, application Great Britain
February 28, 1951

6 Claims. (Cl. 19—131)

The invention has reference to the drafting apparatus used in textile spinning, doubling and twisting machines, such apparatus being of the known type in which the sliver, roving or the like is conducted in its passage through the drafting zone between the forwardly moving surfaces of an endless travelling apron and a single roller about an arc of the surface of which said apron is stretched, the apron being trained between two spaced members of which the rearmost is a roller (the "apron-driving roller") pressed against said single roller to provide a positive driving nip for the apron and a positive restraining nip for the trailing ends of the fibres composing the sliver, roving or the like, whilst the other member (the "foremost apron guiding-member") is a bar or a small diameter roller located in an advanced position spaced from the said single roller and nearer to the nip of the next line of drafting rollers. The present invention has for its object to provide improved means whereby a drafting apparatus of said type may be adapted for processing a wide range of alternative lengths of staple without entailing a complicated adjustment of its elements or the replacement of the principal parts of the drafting mechanism.

In a textile drafting apparatus of the type referred to, the invention provides that the leading edge or hose of the apron where it passes over the foremost apron-guiding member shall be adjustable in position both with respect to its distance from the nip of the next following drafting rollers and to the plane containing the nip of the next following drafting rollers and the nip of the apron driving roller, thereby simultaneously affording an adjustment of the length of the arc of contact between the apron and the single roller over which the apron is stretched.

The invention provides improved means by which such adjustment of the position of the nose of the apron may be effected. Such means may consist of a foremost apron-guiding member formed preferably as a bar of non-circular cross-sectional shape, capable of being rotated about its longitudinal axis and fixed in any desired setting. Alternatively, a bar or roller of circular section may be capable of being moved laterally with components of motion in the vertical and horizontal planes containing its longitudinal axis. Another alternative method of carrying the invention into effect consists in substituting for the foremost apron-guiding member other members of different cross-sectional shapes and/or dimensions providing alternative positions for the nose of the apron.

It is convenient to employ an arrangement comprising an upper apron working in conjunction with a single lower roller, since this permits all the upper drafting elements and the apron assembly, including its foremost guiding-member and the apron-guiding roller, to be carried by a common supporting arm pivoted on a fixed part of the frame and adapted to be raised to and retained in an elevated position giving uninterrupted access to the lower drafting elements. It is also possible in such an arrangement to utilise the common supporting arm for the sus-

2

pension of selvedge guides in close proximity to the roller nips and having means whereby said guides may either partake automatically of the traversing movement of the fibre-body under treatment or be traversed positively by mechanism expressly provided for that purpose.

Various alternative embodiments of the invention are hereinafter described with reference to the accompanying drawings, in which Fig. 1 is a fore-and-aft section of a textile drafting apparatus incorporating two drafting zones

10 using three lines of rollers. Fig. 2 is a fragmentary detail illustrating an alternative method to that shown in Fig. 1 of mounting the foremost apron-guiding member. Figs. 3 and 4 are fragmentary perspective views, respectively from front and rear, of the apron system shown in Fig. 1. 15 The apparatus shown in Fig. 1 comprises a roller-stand 1, carrying in bearings 2, 3 and 4, respectively, three lines of bottom rollers, viz. the feed roller 5, the intermediate roller 6 and the front fluted roller 7. Also mounted on the roller-stand 1, is a pivotal supporting arm 8 by which the upper drafting elements are carried in bearings 9, 10, 11 and 12. The arm 8 is of inverted channel-section (see Fig. 4) and the bearings 9, 10 and 11 are 20 slidable thereon in a fore-and-aft direction. Said bearings 9 to 12 respectively support the upper feed roller 13, the apron-guiding roller 14, the foremost apron-guiding member 15 and the upper front roller 16. A continuous apron 17 is stretched over the roller 14 and the guiding member 15, condensers 18 and 19 are mounted on the bearings 2 and 3 so as to occupy positions on the intake side of 25 the nip of the respective rollers 5 and 6, and a selvedge guide 8a is supported at the rear end of the arm 8. The arm 8, together with the members carried thereby as aforesaid, is rockable toward and away from the lower elements, including the roller 6.

30 35 The settings of the bearings 9, 10 and 11 are fixed to provide the desired inter-roller spacing, according to the length of staple of the material under treatment, by means of setscrews 20, 21 and 22, respectively.

The lower intermediate roller 6 is of substantially 40 larger diameter than is the conventional drafting roller occupying this position, and it is preferably provided with a soft covering or tire of synthetic rubber or other similarly resilient durable material. This roller is conveniently constituted by a shaft 23 upon which are fixed 45 ground steel sleeves 61 spaced in accordance with the spindle gauge, each such sleeve being provided with a covering or tire 62 as aforesaid. Said shaft 23 may extend continuously throughout the length of the machine, or of a section thereof, means being provided for driving 50 it at the appropriate speed for intake of the roving or sliver to be drafted. It is desirable that said lower roller 6 should be of larger diameter than the next succeeding lower roller encountered by the fibres.

The apron-guiding roller 14 is a plain roller, having 55 end-flanges 24 which serve to guide the apron 17 truly over its surface and also to locate the apron with respect to the lower roller 6 over which it is stretched, said flanges 24 extending radially to overlap the ends of the tire 62 of the lower roller 6. The foremost apron-guiding member 15 and the rear flanged driving roller 14 are so disposed with reference to the large lower roller 6 that the apron 17 is stretched with its under-surface around a substantial arc of the upper surface of the latter. The flanged roller 14 presses the apron against the large lower 60 roller 6, thereby providing the necessary positive nip whereby the apron 17 is driven forwardly on its underside.

The foremost apron-guiding member 15 is a bar of non-circular cross-sectional shape having one axis longer than the other; this bar is normally stationary, its edges 70 being rounded to facilitate the passage of the apron about it, but it may be rotated about its longitudinal axis by releasing the setscrew 25, and raised or lowered by re-

leasing the setscrew 26, when necessary for the purpose of regulating the position of the nose of the apron system (a) with respect to its distance from the nip of the next line of rollers 7, 16, and (b) with respect to the plane containing the nip of the rollers 7, 16 and the nip of the apron-guiding roller 14 with the roller 6, simultaneously affording an adjustment of the length of the arc of contact of the apron 17 with the roller 6. If desired, the bar 15 may be arranged to be slightly off-set from its axis of rotation in the bearing 11.

The fibres are conducted between the upper surface of the large lower roller 6 and the under-surface of the apron 17, which conforms to the curvature of said roller 6, over a substantial, though variable, arc of said roller. From the point at which the apron 17 leaves said lower roller 6, the body of fibres is unsupported from beneath and the control over the fibres in their relative movement due to the drafting effect is limited to that which is exercised by their contact with the under-surface of the apron 17 until arriving at the nose of the member 15.

When very short staples are being processed, the foremost apron-guiding member 15 is adjusted so as to bring the nose of the apron 17 close to the nip of the next line of drafting rollers 7, 16, thus automatically reducing the length of the arc of contact between the apron 17 and the single lower roller 6 and diminishing the extent to which the apron nose is displaced below the yarn line. Conversely, when longer staples are being processed, said guiding-member 15 is adjusted so as to withdraw the nose of the apron 17 from the next roller nip and thereby to increase the length of the arc of contact between the apron 17 and the lower roller 6, automatically increasing the displacement of the apron nose below the yarn line and, by deflecting the fibre-body around the apron nose, giving enhanced control over the fibres in the comparatively long distance separating the apron-driving nip and the nip of the next rollers 7, 16.

The apparatus may be adapted for treating fibres of supernormal staple lengths by shifting the apron system 14, 17, 15 bodily in a fore-and-aft direction, the flanged idler 14 being maintained always in driving contact with the large lower roller 6, and the foremost guiding-member 15 being always so located that the apron 17 leaves the surface of said large lower roller 6 before arriving at said guiding-member 15. Where it is necessary to increase or decrease the effective length of the apron-system itself, the apron guiding roller 14 and the foremost guiding-member 15 may be adjusted independently of each other, and in such case an idler roller or pulley may be provided for maintaining the correct operating tension of the apron; such idler roller might, if desired, also perform the function of an apron clearer.

In the modification shown in Fig. 2 the bearings of the members 14 and 15 are carried by a common element or bracket 27; this arrangement does not however permit independent or relative fore and aft adjustment of said bearings.

To enable the apparatus to be used for drafting a wide variety of staple length of fibres, provision is made for decreasing the loading pressure between the flanged apron-roller and the large lower roller, in such manner as to permit a "slip draft" to be employed. The roller 14, in common with the rollers 13 and 16, is conveniently pressed against its cooperating element 6 by means of a compression spring 28 housed in the bearing 10, and the loading pressure of said spring may be varied as aforesaid by regulating the degree of compression of said spring 28 by a screw 29.

The arrangement whereby all the fibre-controlling means are mounted upon the loaded arm 8 substantially simplifies the problem of manipulating these parts of the mechanism during cleaning and correspondingly reduces the work load on the operative.

What we claim as our invention and desire to secure by Letters Patent is:

1. A drafting apparatus comprising, in combination, a large lower drafting roller, an apron opposed to said roller and bearing against it from above over an extensive arc for pressing the fibers against the roller and for driving the apron, an apron guiding roller disposed above and behind the lower drafting roller, a forward guide for the apron, an advance pair of drafting rollers beyond the forward guide, the forward guide being spaced forwardly away from said lower drafting roller, means for supporting and adjusting the forward guide in position independently of said apron guiding roller, and both with respect to its distance from the nip of the advance pair of drafting rollers, with respect to the plane containing said nip and the nip of said large lower drafting roller, and with respect to the nip of the apron guiding roller, thereby simultaneously affording an adjustment of the length of the arc of contact between the apron and the single drafting roller over which the apron is stretched.

10 2. A drafting apparatus comprising, in combination, a large lower drafting roller, an apron opposed to said roller and bearing against it from above over an extensive arc for pressing the fibers against the roller and for driving the apron, an apron guiding roller disposed above

15 and behind the lower drafting roller, a forward guide for the apron, an advance pair of drafting rollers beyond the forward guide, the forward guide being spaced forwardly away from said lower drafting roller, and means for supporting and adjusting the forward guide in position,

20 independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched.

25 3. A drafting apparatus comprising, in combination, a large lower drafting roller, an apron opposed to said roller and bearing against it from above over an extensive arc for pressing the fibers against the roller and for driving the apron, an apron guiding roller disposed above

30 and behind the lower drafting roller, a forward guide for the apron, an advance pair of drafting rollers beyond the forward guide, the forward guide being spaced forwardly away from said lower drafting roller, and means for supporting and adjusting the forward guide in position,

35 independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched,

40 the forward apron guide consisting of a bar of non-circular cross sectional shape and the supporting and adjusting means therefor comprising means for rotatively supporting the bar and securing it in different positions of rotative adjustment, and means for setting the bar supporting means toward and from the nip of the advance pair of drafting rollers.

45 3. A drafting apparatus comprising, in combination, a large lower drafting roller, an apron opposed to said roller and bearing against it from above over an extensive arc for pressing the fibers against the roller and for driving the apron, an apron guiding roller disposed above

50 and behind the lower drafting roller, a forward guide for the apron, an advance pair of drafting rollers beyond the forward guide, the forward guide being spaced forwardly away from said lower drafting roller, means for supporting and adjusting the forward guide in position,

55 independently of said apron guiding roller, and with respect to its distance from the nip of the advance pair of drafting rollers, and with respect to the plane containing said nip and the nip of said large lower drafting roller, thereby simultaneously affording an adjustment of the arc of contact between the apron and the single drafting roller over which the apron is stretched,

60 a rockable upper arm movable toward and from the single large lower drafting roller, and means supporting the apron guiding roller and the forward apron guide from said arm with the apron extending between them.

65 4. A drafting apparatus comprising, in combination, a large lower drafting roller, an apron opposed to said roller and bearing against it from above over an extensive arc for pressing the fibers against the roller and for driving the apron, an apron guiding roller disposed above

65 and behind the lower drafting roller, a forward guide for the apron, an advance pair of drafting rollers beyond the forward guide, the forward guide being spaced forwardly away from said lower drafting roller, and means for supporting and adjusting the forward guide in position,

70 independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched.

75 5. A drafting apparatus comprising, in combination, a large lower drafting roller, an apron opposed to said roller and bearing against it from above over an extensive arc for pressing the fibers against the roller and for driving the apron, an apron guiding roller disposed above

80 and behind the lower drafting roller, a forward guide for the apron, an advance pair of drafting rollers beyond the forward guide, the forward guide being spaced forwardly away from said lower drafting roller, and means for supporting and adjusting the forward guide in position,

85 independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched.

with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched, a rockable upper arm movable toward and from the single large lower drafting roller, and means supporting the apron guiding roller and the forward apron guide from said arm with the apron extending between them.

5. A drafting apparatus comprising, in combination, a large lower drafting roller, an apron opposed to said roller and bearing against it from above over an extensive arc for pressing the fibers against the roller and for driving the apron, an apron guiding roller disposed above and behind the lower drafting roller, a forward guide for the apron, an advance pair of drafting rollers beyond the forward guide, the forward guide being spaced forwardly away from said lower drafting roller, means for supporting and adjusting the forward guide in position, independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched, a rockable upper arm movable toward and from the single large lower drafting roller about an axis parallel to the axis of said large lower drafting roller, the apron guiding roller and the forward apron guide being supported by said arm with the apron extending between them, and the guide supporting and adjusting means comprising a bracket mounted on the arm, and a bearing for the forward guide mounted on the bracket with capacity for adjustment at right angles to the plane containing the longitudinal axis of the supporting arm.

6. A drafting apparatus comprising, in combination, 35 a large lower drafting roller, an apron opposed to said

roller and bearing against it from above over an extensive arc for pressing the fibers against the roller and for driving the apron, an apron guiding roller disposed above and behind the lower drafting roller, a forward guide for the apron, an advance pair of drafting rollers beyond the forward guide, the forward guide being spaced forwardly away from said lower drafting roller, means for supporting and adjusting the forward guide in position, independently of said apron guiding roller, and with respect to its distance from the nip of the advance pair of drafting rollers, and with respect to the plane containing said nip and the nip of said large lower drafting roller, thereby simultaneously affording an adjustment of the length of the arc of contact between the apron and the single drafting roller over which the apron is stretched, a rockable upper arm movable toward and from the single large lower drafting roller about an axis parallel to the axis of said large lower drafting roller, the apron guiding roller and the forward apron guide being supported by said arm with the apron extending between them, and the guide supporting and adjusting means comprising a bracket mounted on the arm, and a bearing for the forward guide mounted on the bracket with capacity for adjustment at right angles to the plane containing the longitudinal axis of the supporting arm.
